SIGNAL DEVICE

Kasimier W. Mozur, Erie, Pa.

Application April 16, 1929, Serial No. 355,498

3 Claims. (Cl. 177—329)

It is desirable with automobiles to indicate the intention of the operator to turn and it is also desirable to have the device such that it may be conveniently actuated by the operator. The present invention is designed to effect this purpose. Features and details of the invention will appear from the specification and claims.

A preferred embodiment of the invention is illustrated in the accompanying drawings as follows:—

Fig. 1 shows a sectional view on the line 1—1 in Fig. 2.

Fig. 2 a front elevation of the device with the cover removed.

Fig. 3 a detail of a reversing mechanism for the motor.

Fig. 4 an enlarged section on the line 4—4 in Fig. 3.

Fig. 5 a perspective view of a detail of a pivot pin shown in Fig. 4.

Fig. 6 a view of one of the supporting plates of the frame.

Fig. 7 a detail of one of the reversing discs.

Fig. 8 an outline of the reversing contacts of the reversing switch.

Fig. 9 the disc carrying the reversing contact plates.

Fig. 10 a perspective view of the reversing pawls.

Fig. 11 a section on the line 11—11 in Fig. 1.

Fig. 12 a section on the line 12—12 in Fig. 11.

Fig. 13 a detached view of the illuminated display shell.

Fig. 14 an outline showing the mounting on the automobile in switch position.

1 marks the case. This is ordinarily secured to the side 2 of the automobile body. 3 marks the cover. This is pivotally mounted on the case by means of a pivot bolt 4. A link 5 is pivotally connected at 6 with the cover and by a pin 7 with a link 8. The link 8 is pivotally connected to the case at 9. A link 10 is connected at 10a with the link 8 and at 11 with a lever 12. The lever 12 is fulcrumed at 13 on a post 14 carried by the case. The lower end of the lever is connected with a lever 15 by a pin and slot connection 16. The lever 15 is fulcrumed at 15a on a post 15b extending from the case. The upper end of the lever 15 has a slot 17 through which a crank pin 18 extends. The crank pin is carried by an arm 19 and the arm 19 is fixed on a shaft 20. A gear 21 is also fixed on the shaft 20 and meshes with a gear 22. The gear 22 is mounted on a shaft 23 extending from a motor frame 24. The gear 22 is fixed with a gear 25 and the gear 25 meshes with a gear 26. The gear 26 is mounted on a shaft 27

which forms the rotor shaft 29 mounted in the frame 24. The link movement which is described as being driven by the motor is designed to open and close the cover as the motor is reversed. Wires 30 and 30a are controlled by a switch 31 and are connected, or disconnected, by the switch with a wire 32 extending to a battery 33. A wire 34 extends from the battery to a post 34a grounding the line 34. The wires 30a and 30 lead to posts 35 and 36 respectively and these posts have spring contact plates 37 and 37a respectively. A swinging contact finger 38 is adapted to engage and form contact with the contact plates 37a and 37.

The finger 38 is mounted on a pin 39. An insulating disc 40 is connected with the finger 38 in a manner hereinafter described. The disc 40 carries reversing contact segments 41 and 42 which operate over contact pins 43 and 44 respectively. The pins 43 and 44 are connected by wires 45 and 45a with the brushes of the motor. The pin 39 extends through a squared hole in the plate 24a of the motor frame 24 and the pins 43 and 44 extend through openings in an insulated plate 47. A pin 46a similar to the pin 43 is connected by a wire 46b with the post 34a and a pin 46 extends through an opening and is carried by the disc 47, the pins 46 and 46a being adapted to be engaged by the contact segments 41 and 42, as clearly shown in Fig. 8, to effect the reversal of the motor, the wire 46c from the pin 46 extending to the motor field coil and from it to the ground.

The finger 38 has an extension 48 which terminates in a slotted end 49, the slot of which engages a pin 50 carried by an arm 51. The arm 51 is fixed on the shaft 20 and is, therefore, driven by the motor.

A projection 52 is arranged on the disc 40 and connected by springs 53 and 54 with the finger 38 and extension 48. The disc has catch shoulders 55 and 56 which are adapted to engage pawls 57 and 58 pivotally mounted on a screw 59. A spring 60 connects the pawls and yieldingly presses them toward the disc 40. Knock-out pins 61 and 62 extend from the pawls 57 and 58 and are in the path of the finger 38 and extension 48.

The operation of this reversing mechanism is as follows:—With the switch set to the wire 30 as shown the line is grounded through the plate 105, finger 38. The circuit through the wire 32, battery wire 34, line wire 46b to the pin 46a leads by way of the segment 42 to the pin 44 which is connected by the wire 45a to one of the brushes (not shown) of the motor. The opposing

- brush connection 45 leads by way of the segment 41 to the pin 46 and from it to the field coil of the motor and thence to the ground completing the circuit. As soon as this circuit is completed, 5 the motor starts its operation and with this operation starts the finger 38 and extension 48, the elongated end of the lever maintaining contact with the finger 37a and during this travel the spring 54 is tensioned drawing on the plate 40. 10 The movement of the plate, however, is retarded, or resisted by the pawl 58. When the extension reaches the knock-out pin 62 it withdraws the pawl 58 releasing the plate 40 and the plate then snaps, reversing the segments 41 and 42. There 15 is at this moment sufficient over-run of the motor to complete the movement of the part 38 so as to break its contact from the plate 37a. This movement closes the cover and cuts out the display of the signal as hereinafter described. 20 To open the cover the switch 31 is rocked closing the switch with the line 30a and opening the switch with the line 30. At this point the finger 38 is under the post 37 and exactly the same cycle takes place in reverse direction as above described 25 finally leaving the parts in the position shown in the drawings. It will be understood that the switch 31 is such that when depressed it closes the circuit with the wires 30 and 31. 30 An electric light 63 is connected by a wire 64 with the post 34a. The opposite side of the light is connected by a contact finger 66 with a post 67. This post 67 is secured in an insulating block 68 carried by the hinge pin 4 of the cover. As the cover closes the contact plate 66 moves 35 off the post 67 on to the insulated block and thus cuts out the light and as the cover is opened the plate reaching the post automatically turns on the light. The rear end of the cover has a curved portion which is designed to contact with the screw 67 if desired. The bolt 4 on which the cover is mounted carries the block 68, the block 68 being fixed on the bolt by the contact screw 67. The bolt has a frictional fit with the sides 40 of the cover which permits it to be turned to change the position of the contact screw 67. If, therefore, it is turned counter-clockwise, as observed in Fig. 12 one-eighth of a revolution it will be in contact with the plate 66 with the cover closed and will contact the rear end of the cover 45 with the cover open so that so long as current is in the circuit the light will continue. The cover is provided with glass covered openings 65 which are properly colored for parking lights. If, therefore, it is desired to use this light as a 50 parking light the screw 67 is turned one-eighth revolution from what is shown and under these conditions the light continues at all times serving as a parking light or in running conditions as a signal light. 55 A display device is formed of U-shaped segments 69 of transparent, preferably colored, material. These segments are pivoted together at 60 65 70 75 80 85 90 95 100 105 110 115 120 125 130 135 140 145 150
- 70 and open and close by a fanwise movement. The lower segment is secured by a screw 71 to the rear face of the case and the outer segment by a pin 72 extending through a perforation 73 in the upper U section of the display device. 80 The pin 72 is secured in the cover. It will be noted that the lever and link system heretofore described which communicates the motion of the motor to the cover in opening and closing the same is arranged within the U-shaped sections of the display device and thus concealed. It will also be observed that the light 63 is arranged to radiate light to the inner surfaces of the walls of the U-section, the U-sections forming a space open to the light. In order to strengthen the U-sections struts 74 extend from the links 5 and 8 and brace the sections near their periphery. 85 What I claim as new is:—
1. In a signaling device, an elongated casing having an open side, a cover for said open side pivoted at one end to said casing, a signaling element including a plurality of nesting U-shaped transparent members pivoted at their similar leg-portions in the casing adjacent to the cover pivot, said casing, members and cover being provided with means for spreading the members fanwise between the casing and cover when the latter is opened and means within the casing for moving the cover to open and closed positions. 95
2. In a signaling device, an elongated casing having an open side, a cover for said open side pivoted at one end to said casing, a signaling element including a plurality of nesting U-shaped transparent members pivoted at their similar leg-portions in the casing adjacent to the cover pivot, said casing, members and cover being provided with means for spreading the members fanwise between the casing and cover when the latter is opened, means within the casing for moving the cover to open and closed positions, and an electric lamp mounted on the cover between the planes of the legs of the signaling device. 105
3. In a signaling device, an elongated casing having an open side, a cover for said open side pivoted at one end to said casing, said cover having flanged sides provided with apertures and transparent plates closing said apertures, a signaling element including a plurality of nesting U-shaped transparent members pivoted at their similar leg-portions in the casing adjacent to the cover pivot, said casing, members and cover being provided with means for spreading the members fanwise between the casing and cover when the latter is opened, means within the casing for moving the cover to open and closed positions, an electric lamp, and means mounting the lamp in the cover between the transparent plates and between the planes of the legs of the signaling device. 115
